UNITED STATES PATENT OFFICE.

CHARLES E. C. EDEY, OF TACOMA, WASHINGTON, ASSIGNOR OF ONE-FOURTH TO ALFRED S. EDEY AND ONE-FOURTH TO DUNBAR F. EDEY, BOTH OF TACOMA, WASHINGTON.

BURGLAR-ALARM.

No. 909,851.

Specification of Letters Patent.

Patented Jan. 12, 1909.

Application filed December 16, 1907. Serial No. 406,761.

To all whom it may concern:

Be it known that I, CHARLES E. C. EDEY, a citizen of the United States, residing at Tacoma, in the county of Pierce and State of Washington, have invented certain new and useful Improvements in Burglar-Alarms; and I do hereby declare the following to be a full, clear, and exact description of the invention, such as will enable others skilled in the art to which it appertains to make and use the same.

This invention relates to improvements in alarms and particularly to burglar alarms that are designed to be put in operation upon the opening of a door, window, or the like by an unauthorized person.

The invention further comprises the provision of an alarm mechanism, a cam for regulating the action of the alarm mechanism, and means for regulating the position of the cam.

The invention further comprises the provision of a pivotally mounted lever designed to be moved by a door or the like to operate a cam so that when the door operates the lever the cam will be moved, the movement of the cam being designed to throw into or out of operation an alarm.

The invention still further comprises the provision of alarm mechanism designed to be automatically set into operation, means for throwing the operating means out of operative position, and a push button and connecting mechanism for using the alarm as an ordinary door bell.

The object in view is the provision of an alarm that may be thrown to an inoperative position during the day and again put in operative position during the night, so that an unauthorized person cannot enter without sounding the alarm.

Another object in view is the provision of an alarm mechanism and means for operating the same, together with a push button and connecting mechanism arranged to use the alarm mechanism as an ordinary door bell.

With these and other objects in view the invention comprises certain novel constructions, combinations and arrangements of parts that will be hereinafter more fully described and claimed.

In the accompanying drawing:—Figure 1 is a perspective fragmentary view of a door and jamb with an alarm formed according to the present invention secured thereto. Fig.

2 is a vertical section through the alarm and surrounding mechanism taken approximately on line 2—2 of Fig. 3. Fig. 3 is a top plan view of an alarm mechanism formed according to the present invention, the mechanism being shown in an inoperative position. Fig. 4 is a top plan view of an alarm mechanism formed according to the present invention, the same being shown set. Fig. 5 is a detail view showing the lever in normal position. Fig. 6 is a similar view showing the lever moved to position to spring the alarm. Fig. 7 is a detail view of the lever for rendering the alarm ineffective.

In providing a burglar alarm it is desirable to so construct the same as to make a device that will give a positive alarm and one that is comparatively cheap and easily secured in place. In the accompanying drawings will be seen the preferred embodiment of my invention which is designed to accomplish these results and others as hereinafter pointed out.

Referring more particularly to the drawings, 1 indicates a door jamb or the like to which the alarm or bell 2 is designed to be secured.

3 is a door having secured thereto a stop 4 that engages the end of lever 5. Lever 5 is designed to be pivotally mounted at 6 and extend over to a position opposite the escapement wheel 7, forming part of the mechanism of bell 2. In regard to bell 2, it is to be noted that any desired kind of bell may be used which is provided with an escapement as 7.

Secured to the end of lever 5 at a position opposite to escapement 7, and formed integral with lever 5 is a cam 8.

A spring 9 is designed to be placed against the outer casing or base of bell 2 and bears at one end against a stop 10 and is rigidly secured to lever 5 for normally holding cam 8 beneath spring 11 and in proximity to escapement wheel 7. Spring 9 is preferably formed from spring wire and given a turn around pivotal member 6, as clearly seen in Figs. 3 and 4.

The lever 5 is formed opposite the end to which cam 8 is secured with an extension 12 that is designed to be engaged by stop 4 when the door is closed.

Secured to the base 13 of bell 2 is a spring 11 that is preferably secured at 14 and extends entirely across the base 13, an aperture 15 being formed for accommodating the

shaft 16 of the bell. Spring 11 is provided with an extension or catch 17 that acts as a pawl for engaging the teeth of escapement wheel 7. Preferably the pawl 17 is pressed 5 or stamped from the spring 11 and is so formed as to project in the way or path of movement of escapement wheel 7 so that whenever it is desired to permit escapement wheel 7 to move and ring the bell, spring 11 10 must be moved for raising pawl 17 above the escapement wheel. Casing 13 is formed with an aperture 18 through which cam 8 is designed to pass for engaging spring 11 for raising pawl 17 above escapement wheel 7, as clearly seen in Fig. 2. Whenever door 3 is closed, stop 4 engages the end of lever 5, and forces the same inward as seen in Fig. 3, and cam 8 is moved out as seen in Figs. 2 and 3, and spring 11 is permitted to bring 15 pawl 17 into engagement with escapement wheel 7. When door 3 is open, spring 9 will force the end of lever 5, carrying member 12, outward and also force inward cam 8, which in turn will engage the end of spring 20 11 and force upward its extension pawl 17, so that escapement wheel 7 is permitted to rotate freely. When escapement wheel 7 is permitted to rotate, the remaining mechanism of the bell is permitted to operate for 25 sounding or ringing the bell in the usual manner. This ringing of the bell will continue until the spring, or other motive power used, is exhausted or until cam 8 is removed from engagement with spring 11.

30 35 It is designed to use the bell 2 as a door bell as well as a burglar alarm and in order to prevent the bell from ringing when the door is opened, a lever 19 is pivotally mounted at 20, in a securing member 21. Lever 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

presses against spring 11 which now acts as a resilient spring for the door bell, so that when power is applied to push button 24, the same will be exerted upon spring 11 for moving the same and raising pawl 17 out of engagement with escapement wheel 7. When pawl 17 is out of engagement with escapement wheel 7, bell 2 will ring as heretofore described, but when the button 24 is released the spring releases the pawl 17 to engagement with the wheel 7, thus stopping the ringing of the bell.

The operation of the burglar alarm is as follows:—On the door being opened by a burglar or other unauthorized person, the 80 portion 12 (see Fig. 4) is thrown out by the spring 9, as shown in said figure, and the opposite end of lever 5, having the cam 8, as better shown in Fig. 3, passes said cam 8 under that part of the spring 11, bearing the 85 hook out of engagement with the wheel 7, allowing the wheel 7 to rotate and the alarm to ring.

To change the burglar alarm to a door-bell it is only necessary to throw out the 90 pawl 19 as shown in Fig. 3, whereupon its downward portion, as at 23, takes against the inner edge of lever 5 and throws that end of the lever outward, and its laterally raised cam 8 away from the pawl 17. Being locked 95 in that position, the alarm is inoperative as an alarm, but as will be readily seen, on reference to Fig. 2, is still operative as a door bell, and on pushing the button at 24 the spring 11 with its engaging pawl 17 is drawn 100 upward away from the wheel 7. When this happens, wheel 7 rotates and the bell rings until the pressure being removed from the button 24, the pawl 17 returns to its engagement with wheel 7 and, locking said wheel, 105 stops the ringing of the bell. By this construction the bell will ring simply as a door bell and will ring only as long as button 24 is pressed and will cease to ring immediately upon the releasing of the button. It will be 110 understood that push button 24 will operate bell 2, even though lever 19 is in the position shown in Fig. 4, and the burglar alarm mechanism is set for operation.

What I claim is:—

1. In a burglar alarm the combination with a door, of an alarm formed with an escapement wheel, a catch for normally preventing rotation of said escapement wheel, a spring for supporting and holding in position said catch, a lever provided with an end adapted to engage with said door when closed, and an opposite end, said opposite end having a cam to operate the catch, and a spring to hold the lever in normal contact with the door when closed.

2. In a burglar alarm the combination with a door, of an alarm mechanism including an escapement wheel, means for normally preventing rotation of said wheel, a

lever for disengaging the said means upon opening of said door, the said lever being pivoted intermediate its ends and having one end arranged for engagement by the 5 door and the other end engaged normally with the said means, and a pivoted cam lever movable to position to engage the first mentioned lever to one side of its pivot and hold its ends out of engagement with the door 10 and the escapement holding means.

3. In a burglar alarm the combination with a door, of an escapement mechanism including an escapement wheel, a leaf spring provided with a projection normally en-

gaged with the escapement wheel to prevent 15 the rotation thereof, a pivoted lever arranged at one end for engagement with said door and provided at its other end with a cam portion engageable with the said projection to disengage the same from the escapement wheel, and a cam lever for rendering said pivoted lever inoperative.

In testimony whereof I affix my signature in presence of two witnesses.

CHARLES E. C. EDEY.
